CLAIM

The ornamental design for a bait box lure, as shown and described.

DESCRIPTION

FIG. 1 is a perspective view of the bait box lure showing our new design;

FIG. 2 is a left side view of my design;

FIG. 3 is a top view of my design;

FIG. 4 is a bottom view of my design;

FIG. 5 is a front view of my design; and,

FIG. 6 is a rear view of my design.

The features shown in broken lines in FIG. 1 are shown for illustrative purpose only and form no part of the claimed design.
